FRANK J. PIOCH, OF SAN FRANCISCO, CALIFORNIA.

GAS-HEATED RADIATOR.

1,224,784.

Specification of Letters Patent.

Patented May 1, 1917.

Application filed June 14, 1916. Serial No. 103,656.

To all whom it may concern:

Be it known that I, FRANK J. PIOCH, a citizen of the United States, residing in the city and county of San Francisco and 5 State of California, have invented new and useful Improvements in Gas-Heated Radiators, of which the following is a specification.

This invention relates to a gas heated 10 radiator and particularly to improvements over my co-pending application entitled "Gas heated radiator," filed January 31, 1916, Serial Number 75,292.

One of the objects of the present invention is to provide an improved form of 15 damper box and a damper of novel construction operable in conjunction with same. Another object of the invention is to provide a vertically adjustable discharge vent and, 20 furthermore, to provide means for raising and lowering the damper box to register with same. Further objects will hereinafter appear.

The invention consists of the parts and 25 the construction and combination of parts as hereinafter more fully described and claimed, having reference to the accompanying drawings, in which—

Figure 1 is a front elevation of a gas heated 30 radiator partly in section.

Fig. 2 is a front view of the radiator section which contains the burner and damper box.

Fig. 3 is a rear vertical section on line 35 3—3 of Fig. 4.

Fig. 4 is a central, vertical section on line 4—4 of Fig. 2.

Fig. 5 is a horizontal section on line 5—5 of Fig. 4.

40 Referring to the drawings in detail, A indicates in general a gas heated radiator and 2 a central section provided with a burner 3, a damper box 4, an adjustable discharge elbow 5 and a re-heating tube 6.

45 Positioned on each side of the central section is a plurality of radiating tubes 7 which are connected at their upper ends with the upper end of the central section through a central passage 8 and at their 50 lower ends through a passage 9 with a return chamber 10 formed in the lower part of the central section. Each radiating tube 7 is divided to form two passages and said passages communicate at their upper and

lower ends with the longitudinal passages 55 8 and 9, thus permitting the formation of a large heating area. The sections 7 are, furthermore, secured with relation to the central section by means of a pair of tie rods 11 and 12, one passing through the upper 60 longitudinal passage 8 and one through the lower longitudinal passage 9; each end section being provided with a removable plug 13 to close the longitudinal passages and also to permit the insertion of the rods 11 65 and 12.

The mounting of the damper box 4 and the coöperating damper 15, together with the adjustable discharge vent 5, forms one of the most important features of the present invention. The damper box 4 is in this instance rectangular in cross section and its length is approximately such as shown in Figs. 1 and 4. The rear side of the damper box is provided with an opening 16 70 75 which communicates with a discharge vent 17 formed in a plate 18.

The rear side of the central section containing the damper box is provided with an oblong slot 19 (see Figs. 3 and 4), through 80 which a boss 20, formed on the rear side of the damper box and surrounding the opening 16, projects. A pair of screws 21, extending through the plate 18 and entering the damper box, permits the plate and box 85 to be clamped together, and as the metal 22 forming the rear side of the central section is interposed between the damper box and the plate, it can be seen that the screws 21 serve as clamps to permit adjustment of the discharge vent 17 and the attached damper box 4 in a vertical direction within the slot 19 and may also be sufficiently tightened to secure the plate 18 90 and attached box 4 in any adjusted position 95 desired.

The damper 15 is pivotally attached, as at 23, to the front edge of the damper box and is so shaped that it normally rests on the seat formed at the upper end of the 100 box to form a closure therefor. It may, however, be raised to form communication between the main chamber formed within the central section and the interior of the damper box, with connected discharge vent 105 17, this raising movement being obtained by means of a rod 24, pivotally attached, as at 25, to a lug formed on one side of

the damper. The lower end of this rod is provided with a handle section 26 which extends through the bottom of the central section a sufficient distance to permit it to be 5 grasped and pulled when it is desired to raise the damper.

The burner 3 is preferably of the "Bunsen" type and its shape and construction may be such as conditions require. This 10 burner when ignited is supplied with air through an opening 27 formed in the bottom of the central section on one side of the return chamber 10 and is also provided for the purpose of permitting the gas pipe 15 to be connected with the burner.

Forming a closure for the return chamber 10 is a removable plate 27^a, and forming a connection between an opening formed in said plate and the lower end of the damper 20 box is a reheating tube 28. Formed in the front side of the central section is an opening, in which is mounted an outwardly swinging door 29. This door is hingedly supported at its upper end by means of a 25 pair of screws 30. It is in this manner free to swing in an outward direction from the lower end and as the whole weight of the door is supported by the screws 30, it can be seen that the door will be self-closing when 30 released.

Heaters of the character here shown are generally provided with comparatively small discharge flues of short lengths. The natural draft created by the comparatively high 35 discharge flues or stacks is, therefore, practically absent and unless an induced draft is started therein considerable trouble is experienced in maintaining the fire within the chamber formed in the central section which 40 will hereinafter be termed the combustion chamber. An induced draft is created in the present instance by the damper 15.

The operation when starting the burner will be as follows: The door 29, mounted 45 on the front side of the central section, is first opened and the burner 3 ignited. The door is then closed and the handle section 26 grasped and pulled in a downward direction to open the damper 15, the damper 50 being held in this position by a hook section 26^a formed on the handle section which is engaged with the front or underside of the central section. The heat from the burner is in this manner permitted to enter directly 55 through the damper opening and damper box into the discharge vent 17, with connected flue, causing this to become heated to such an extent that an induced draft is created. The reheating tube 28 is at the same time 60 heated causing an induced draft to be established at this point which creates a suction through the lower connected passages of the radiating tubes 7.

The moment the reheating tube 28 and the 65 discharge flue have been sufficiently heated,

which takes place in two or three minutes, it is only necessary to close the damper 15 by releasing the handle section 26 with relation to the front edge of the casing. This permits the damper 15 to fall back and close 70 the direct communication between the combustion chamber and the discharge flue. The heat from the burner will now pass through the upper longitudinal passage 8, down through the radiating tubes 7, and 75 then through the lower connecting passage 9 which communicates with the return chamber 10, and is here finally permitted to escape through the reheating tube 6 and the damper box 4, which, as previously described, is connected with the discharge flue 80 through the vent opening 17.

The heat from the burner, when passing through the radiating tubes 7, is naturally cooled down before reaching the return 85 chamber 10 as the heat is absorbed and radiated by the radiating tubes. The draft will, therefore, become more or less sluggish unless reheated by passing through the tube 28 which is mounted directly in the combustion chamber and subjected to the direct heat of the burner 3. A new impetus is thus given the escaping products of combustion and a comparatively high velocity of draft is maintained as long as the burner is in use. 90 Fresh air to support combustion is continuously admitted through the bottom opening 27, thus permitting a perfect operation of the burner 3 and also providing a means for ventilating the room in which the heater is 100 mounted.

The adjustable discharge vent 17 is one of the important features of the present invention as it permits this to be raised or lowered vertically to form an alignment with a permanent discharge vent or opening formed in the wall. The importance of this feature can be readily understood when it is considered that practically all piping and plumbing is placed in a building between the 105 partitions before the plaster or flooring is applied. Now it may happen that a single flooring was intended and that the distance from the bottom of the radiator to the discharge vent is ten inches. The plumber installing the piping can thus figure on placing the outlet of the flue ten inches above the floor joist plus the thickness of the flooring; while it may happen that the owner decides on putting in a double flooring and on top of same a hardwood finish and possibly a heavy rug besides. This would naturally bring the discharge vent of the radiator two or three inches above the now permanently fixed vent openings 110 formed in the wall and would, therefore, either necessitate tearing out the plaster or cutting away the flooring to permit the legs 115 of the radiator to be lowered accordingly. The adjustable damper box and discharge 120 flue 125

130

5 vent 5 here shown positively eliminate this objectionable feature as they may be raised or lowered a considerable distance, this distance being limited only by the length of the slot 19.

10 The damper provided in the present instance is simple in construction and will always close itself when the handle 26 is released.

15 The door constructed and mounted as here shown is also an important feature as it serves the function of a safety valve, that is, it will automatically open and swing outwardly if an explosion should take place in the combustion chamber, thus permitting the force of the explosion to pass directly out of the door without doing any damage.

20 The materials and finish of the several parts of the device here shown may be such as the experience and judgment of the manufacturer may dictate.

25 I wish it understood that various changes in form, proportions and details of construction may be resorted to within the scope of the appended claims, and that I do not wish to limit myself to the specific design and construction here shown.

30 Having thus described my invention, what I claim and desire to secure by Letters Patent is—

35 1. In combination a casing inclosing a combustion chamber, said casing being provided with an opening, a damper box arranged in said casing and engaging the wall thereof around said opening, a plate adapted to fit over said opening on the outside of said casing, said plate being provided with a discharge vent, said damper box being provided with a vent adapted to register 40 with the vent in said plate, said damper box and said plate being adjustable with relation to the opening in said casing, means for securing said damper box and said plate together to grip the wall of the casing therebetween to secure the plate and the vent therein in adjusted position, and means for establishing and controlling direct and intermediate communication between said damper box and said combustion chamber.

45 2. In a heat radiator, a combustion chamber and a return chamber, a plurality of heat-radiating tubes communicating with the combustion chamber at their upper ends and with the return chamber at their lower ends, an adjustable damper box mounted in the combustion chamber, a reheating tube connecting the damper box and return chamber, a discharge flue, and an adjustable plate having a vent opening formed 55 therein and adapted to form communication between the damper box and the discharge flue.

60 3. In a heat radiator, a combustion chamber and a return chamber, a plurality of heat-radiating tubes communicating with

the combustion chamber at their upper ends and with the return chamber at their lower ends, an adjustable damper box mounted in the combustion chamber, a reheating tube connecting the damper box and return chamber, a discharge flue, an adjustable plate having a vent opening formed therein adapted to form communication between the damper box and the discharge flue, a damper pivotally mounted on the upper end 70 of the damper box, and a rod attached to the damper and extending through the lower end of the combustion chamber.

75 4. In a heat radiator, a combustion chamber and a return chamber, a plurality of heat-radiating tubes communicating with the combustion chamber at their upper ends and with the return chamber at their lower ends, an adjustable damper box mounted in the combustion chamber, a reheating tube 80 connecting the damper box and return chamber, a discharge flue, an adjustable plate having a vent opening formed therein adapted to form communication between the damper box and the discharge flue, a damper pivotally mounted on the upper end 85 of the damper box, and a rod attached to the damper and extending through the lower end of the combustion chamber, and a hook-shaped handle extension on the lower end of the 90 rod adapted to secure the damper in its opened position.

95 5. In a heat radiator the combination with a central radiator section and an elongated opening formed in the rear side of 100 the section, of a damper box mounted interiorly of the section, said damper box having an outlet opening formed therein and registering with the elongated opening, a plate having a discharge vent formed therein and mounted exteriorly of the radiator section, said plate being longer than the elongated opening and adapted to form a cover for same, and means for adjusting the plate and damper box vertically and securing the same when adjusted.

105 6. In combination, a casing inclosing a combustion chamber, a return chamber, means maintaining communication between said combustion and said return chamber, 115 an adjustable discharge vent in said casing, and a telescoping connection for establishing communication between said return chamber and said discharge vent, and for adapting itself to the position of said vent when said plate and vent are adjusted.

120 7. In a heat radiator, a casing inclosing a combustion chamber, a return chamber, a plurality of heat-radiating tubes communicating with said combustion chamber at the upper ends and with the return chamber at their lower ends, an adjustable discharge vent in said casing, and a telescoping connection for establishing communication between said return chamber and said dis- 125

charge vent, and for adapting itself to the position of said vent when said plate and vent are adjusted.

8. In a heat radiator, a casing inclosing 5 a combustion chamber and a return chamber, a plurality of heat radiating tubes communicating respectively at their ends with said combustion chamber and said return chamber, said casing being provided with 10 an opening, a plate mounted on said casing and having a discharge vent formed therein and registering with said opening, a telescoping connection for establishing communication between said return chamber

and said vent and for adapting itself to the 15 position of said plate and vent when said plate and vent are adjusted, the ends of the respective sections of said telescoping connection being connected respectively to said return chamber and said plate. 20

In testimony whereof I hereunto set my hand in the presence of two subscribing witnesses.
